UNITED STATES PATENT OFFICE.

HENRY J. HAWVICHORST, OF TULARE, CALIFORNIA.

PNEUMATIC PUMP.

1,347,033.

Specification of Letters Patent. Patented July 20, 1920.

Application filed July 2, 1919. Serial No. 308,245.

To all whom it may concern:

Be it known that I, HENRY JOHN HAWVICHORST, a citizen of the United States, residing at Tulare, in the county of Tulare and State of California, have invented new and useful Improvements in Pneumatic Pumps, of which the following is a specification.

My invention is a pneumatic pump and consists of the novel features herein shown, 10 described and claimed.

The principal object of my invention is to pump oil or water with an air pump at the top of the well and to save the exhaust air to feed the air pump.

15 Figures 1 and 1^A together form a fragmentary sectional elevation of an air lift pump embodying the principles of my invention and showing the pump in operation in the well.

20 Fig. 2 is a fragmentary sectional elevation at the bottom of the well at right angles to Fig. 1^A as indicated by the line 2—2 and looking in the direction indicated by the arrows.

25 Fig. 3 is a horizontal cross section on the lines 3—3 of Figs. 1^A and 2 and looking downwardly as indicated by the arrows.

Fig. 4 is a fragmentary perspective of one of the valve operating constructions.

30 Fig. 5 is a horizontal sectional detail on the line 5—5 of Fig. 4.

Fig. 6 is a fragmentary sectional detail showing the relative location of the valves and valve parts.

35 The pump cylinder consists of an annular wall 1 which is preferably a section of a comparatively large pipe, a cap 2 being screwed upon the lower end of the wall 1 and a cap 3 screwed upon the upper end of

40 the wall 1. The inlet valve casing 4 is screwed through the cap 2 and has a chamber 5, an inlet opening 6 in the bottom leading to the chamber 5, and an intake valve 7 covering the opening 6. A pipe 8^a is screwed

45 through the center of the cap 3 and extends upwardly to a point above the top of the ground, and a stuffing box 8^b is formed upon the upper end of the pipe 8^a. A rod 8 is slidingly mounted through the pipe 8^a and

50 through the stuffing box 8^b. A float 9 is placed in a cylinder around the rod 8, an

upper stop 10 is fixed upon the rod 8 above the float, and a lower stop 11 is fixed upon the rod 8 below the float, the said stops 10 and 11 being a sufficient distance apart to 55 give the float the proper vertical movement so that when the cylinder fills with the liquid the float will go up and engage the stop 10 and raise the rod 8 so that when the liquid leaves the cylinder the float will strike the 60 stop 11 and the weight of the float will pull the rod 8 downwardly.

An air pipe 12 is connected through the cap 3 to the top of the cylinder chamber 13, and a liquid pipe 14 is fixed through the cap 65 3 and extends to near the bottom of the chamber 13. The cylinder thus constructed is adapted to be mounted in the bottom of a water well or oil well, or at least far enough down in the well to be below the top 70 of the liquid 15. The upper end of the pipe 14 is connected to the check valve casing 16 and an up-flow check valve 17 is mounted in the casing 16. The pump tube 18 is connected to the casing 16 and extends downwardly 75 to a point above the top 19 of the well 20 and the discharge pipe 21 is connected to the upper end of the pipe 18 and leads to any desired point of delivery.

The rod 8 extends upwardly to the fitting 80 22 above the stuffing box 8^b and a cable 23 is connected to the fitting 22 and extends upwardly over guide pulleys 24 and 25 and downwardly to a counterbalancing weight 26. The weight 26 is adapted to balance the 85 weight of the rod 8 so that the float 9 need have only sufficient power to overbalance the weight 26 to force the rod 8 up or down.

The air pipe 12 extends from the cylinder upwardly to a point above the top of the 90 well 20 and to the T 27. A branch pipe 28 extends from the T 27 to the pressure tank 29 and a pipe 30 extends from the T 27 to the exhaust tank 31.

A stop valve 32 is incorporated into the 95 pipe 28 and a stop valve 33 is incorporated into the pipe 30. A blow-off valve 34 is located at the top of the pressure tank 29 and an intake check valve 35 is located at the top of the exhaust tank 31. A pipe 36 100 leads from the exhaust tank 31 to the intake of the pump 37 and a pressure pipe 38 leads

from the discharge end of the pump 37 to the pressure tank 29. The pump 37 is operated by a crank shaft 39 carrying a belt fly-wheel 40 to be driven from any suitable 5 source of power.

A cut-off valve 42 is incorporated into the pipe 36, a branch inlet pipe 43 is connected to the pipe 36 behind the valve 42 and provided with a valve 44 and a secondary inlet 10 check valve 45 so that the valve 42 may be closed and the valve 44 opened to raise the pressure in the tanks 29 and 31 to the desired extent to start the operation of pumping. A pressure gage 46 is connected to the 15 top of the tank 31 and a pressure gage 47 is connected to the top of the tank 29 so as to engage the operating pressure in the tank 29 and the exhaust pressure in the tank 31.

The valves 32 and 33 have ports 48 and 20 49 set at right angles to each other so that when the valves are operated simultaneously one will open when the other closes and vice versa. The ports 48 and 49 are formed in the valve plugs 50 and 51 and operating 25 handles 52 and 53 are rigidly connected to the outer ends of the valve plugs, the handles being set upon the plugs with the plugs arranged with the ports at right angles as shown in Fig. 6.

30 The valve handles 52 and 53 are substantially alike and each handle has a vertical opening 54 through which the cable 23 extends freely and stops 55 and 56 are adjustably fixed upon the cable 23, one below the 35 handle 52 and the other above the handle 52. In a like manner stops 57 and 58 are adjustably fixed upon the cable 23 above and below the handle 53. The stops 55, 56, 57 and 58 are substantially alike and are 40 constructed as shown in Figs. 4 and 5, each stop consisting of half bearings 59 and 60 adapted to grip the cable 23 and a U-clip 61 clamping the half bearings 59 and 60 together and gripping the cable.

45 The stops 55, 56, 57 and 58 are located upon the cable 23 so that when the float 9 goes down to pull the rod 8 downwardly, thereby pulling the cable 23 downwardly, the stop 56 will engage on top of the handle 52 and the stop 58 will engage on top of the handle 53 and pull the handles downwardly as shown on dotted lines in Fig. 1, and thereby closing the valve 32 and opening the valve 33, then the weight of the head of 55 liquid 15 in the well will open the check valve 7 and force the liquid into the cylinder until the float 9 goes up and raises the rod 8 to allow the weight 26 to pull the operating end of the cable 23 upwardly until 60 the stop 55 raises the handle 52 and the stop 57 raises the handle 53, thereby closing the valve 33 and opening the valve 32, then the pressure from the tank 29 will pass downwardly through the pipe 12 into the

cylinder and force the liquid up the pipe 14, 65 thereby opening the check valve 17 and allowing the liquid to pass upwardly above the check valve. When the float 9 goes down the operation is repeated.

The level 62 of the liquid 15 may be 100 70 or 200 feet above the check valve 17, thus giving a high head of liquid and the pressure of the exhaust in the tank 31 need be only a little less than the pressure caused by the high head of liquid. Of course if 75 the head of liquid is low the pressure in the exhaust tank must be correspondingly low. When pumping from deep wells with a high head of liquid a high exhaust pressure may be maintained in the tank 31, thus 80 feeding the intake air to the pump 37 under a comparatively high pressure, and thereby greatly reducing the work of the pump.

The difference between the operating 85 pressure in the tank 29 and the return pressure in the tank 31 need be only great enough to overcome the resistance and the difference between the level 62 of the head of liquid in the well and the elevation at which the liquid is delivered from the pipe 90 21. Of course the greater the difference between the liquid level in the well and the point at which the liquid is to be delivered the greater the difference between the pressure in the tank 29 and the pressure in the 95 tank 31.

Thus I have produced a pneumatic pump adapted to successively lift a liquid from a well and to save the exhaust under pressure for feeding the pump.

100 Various changes may be made without departing from the spirit of my invention as claimed.

I claim:

A pneumatic pump comprising a pump 105 cylinder adapted to be mounted in a liquid in a well and having an intake valve, an air pipe connected to the top of the cylinder, a liquid pipe leading from near the bottom of the cylinder, a check valve in the liquid 110 pipe, a pump tube leading upwardly from the check valve, a rod slidably mounted through the top of the cylinder, a float upon the rod in the cylinder, stops upon the rod above and below the float, the rod extending 115 to a point above the top of the well, a cable connected to the upper end of the rod and extending over guide pulleys, a weight upon the other end of the cable, stops upon the cable, branch pipes connected to the upper 120 end of the air pipe, stop valves in the branch pipes and having plugs with ports at right angles to each other, arms extending from the plugs and engaging the stops upon the cable, an exhaust tank connected to one 125 branch pipe, a pressure tank connected to the other branch pipe, a pipe leading from the exhaust tank to the pump, a pipe leading

from the pump to the pressure tank; so that when the float goes down the exhaust branch will be closed and the pressure branch opened to allow the pressure to force the liquid out of the cylinder up the pump tube, and so that when the float goes up the exhaust branch will be opened and the pressure branch closed, and so that the exhaust air passing through the exhaust branch will go to the exhaust tank and to the pump under pressure.

In testimony whereof I have signed my name to this specification.

HENRY J. HAWVICHORST.
